Primary Examiner—Celia Murphy*Attorney, Agent, or Firm*—Fulwider Patton Lee & Utecht, LLP[57] **CLAIM**

The ornamental design for a shoe midsole, as shown and described.

DESCRIPTION

FIG. 1 is a left side view showing the upper sole of my new design, it being understood that the right side is a mirror image thereof; the broken line showing the sole in FIG. 1 is for illustrative purposes only and forms no part of the claimed design;

FIG. 2 is a bottom plan view thereof;

FIG. 3 is a top plan view thereof;

FIG. 4 is a front view thereof;

FIG. 5 is a back view thereof; and,

FIG. 6 is a perspective view thereof.
